UNITED STATES PATENT OFFICE.

ELLSWORTH A. HAWTHORNE, OF BRIDGEPORT, CONNECTICUT.

LAMP.

1,179,098.

Specification of Letters Patent. Patented Apr. 11, 1916.

Application filed May 22, 1914. Serial No. 840,340.

To all whom it may concern:

Be it known that I, ELLSWORTH A. HAWTHORNE, a citizen of the United States, and a resident of Bridgeport, county of Fairfield, 5 and State of Connecticut, have invented an Improvement in Lamps, of which the following description, in connection with the accompanying drawings, is a specification, like characters on the drawings representing like parts.

This invention relates to lamps, and more especially, though not exclusively, to a vehicle tail lamp of the type wherein the light serves to illuminate a number-plate and a 15 red window or lens at the rear.

My invention will be best understood by reference to the following specification, when taken in connection with the accompanying drawings of several specific embodiments 20 thereof, while its scope will be more particularly pointed out in the appended claims.

In the drawings: Figure 1 is a side elevation of one form of lamp embodying my invention; Fig. 2 is an elevation of the same 25 as viewed from the right side of Fig. 1; Fig. 3 is a plan sectional view on line 3—3 of Fig. 2; Fig. 4 is a detail plan section of one end of the lamp casing, showing a slight modification of the cover fastening means; Fig. 5 is a central, longitudinal sectional view of another form of lamp showing a 30 different type of cover fastening device; Fig. 6 is a bottom plan of the form shown in Fig. 5; Fig. 7 is an elevation of one form of 35 socket locking plate and socket, as viewed from the inside of the casing; Fig. 8 is a similar elevation of another form of socket locking plate and socket; and Fig. 9 is a similar elevation of still another form of 40 socket locking plate and socket.

Referring to the drawings, and to the several embodiments of my invention which I have selected for illustration, I have there shown a lamp comprising a casing 10, within 45 which is suitable light producing means, herein in the form of an electric incandescent bulb 11, the latter being mounted in a tubular socket 12, extending through the casing and threaded into an appropriate supporting bracket 13, which latter is secured to the lamp casing.

The tubular socket may be held against rotation by any other appropriate means, but herein it is provided with means interlocking 50 with a plate inside the casing.

In the form shown in Figs. 2, 3 and 7, there is provided a plate 14, having an aperture 15 to receive the inner end of the lamp socket, and the latter is provided with one or more, herein two notches 16 in its end to receive corresponding teeth or flanges 17, projecting inwardly from the margin of the aperture, whereby the socket, when screwed into place, is securely held against rotation by the plate, which in turn is secured to the 60 inner face of the rear wall of the lamp casing.

Referring to Fig. 8, this form differs from that just described, in that there is provided a plate 18, having an elongated aperture 19, 70 which is formed to receive a correspondingly shaped flange 20 on the lamp socket.

The form shown in Fig. 9 differs from that shown in Fig. 8, in that there is provided a plate 21 having an aperture 22 to receive a flange 23 of the socket as before, but in this case, the plate is provided with a pair of raised flanges 24, projecting inwardly and overlying the flange 23 of the socket, whereby the latter is held against inward movement, as well as against rotation.

In the form shown in Figs. 1, 2 and 3, as well as in that shown in Figs. 5 and 6, the casing is herein provided with an aperture 25, constituting a window, through which a 85 part of the light is intended to be directed upon a number-plate in a wellknown manner, and this opening is herein provided with a light-transmitting element or window 26. This may be held in place by one 90 or more, herein two, straps 27, extending transversely entirely across the opening, and one or more, herein two, flanges 28 located at the respective ends of the opening, and also overlying the window, or light-transmitting element. The latter is made large enough, so that its margin extends beyond the edges of the opening, and overlies the margin of the latter, as will be clearly understood upon an inspection of Figs. 5 100 and 6.

The casing may be otherwise appropriately formed, but herein consists of a single seamless shell pressed or drawn through sheet metal, and having at its rear side an opening 105 which is closed by a cover or door 29, which herein serves as a mounting for a light-transmitting element 30, the latter being herein the usual red window or lens. In each of the forms shown, this cover is provided with 110

a marginal flange 31, overlying the adjacent edge of the casing, and serving to exclude the dust from the latter, as well as to provide a natural finish. This flange, moreover, constitutes a means for giving the cover increased strength and rigidity.

In the form shown in Figs. 1, 2 and 3, the cover is provided with an aperture having an encircling flange 32, forming a seat for the light transmitting element 30. The latter is herein held in place by a plate 33, provided with an aperture 34 of such size that its margin overlaps the margin of the light-transmitting element, and there is interposed between the two a gasket 35, serving to exclude dust and moisture from the interior of the casing. The plate 33 may be secured to the cover 29 by any appropriate means, as for example one or more rivets 36. It will be observed that the plate 33 serves also as a reinforcement for the cover 29.

In the form shown in Figs. 1 to 3, inclusive, the cover is secured in place by a fastening means, including one or more, herein 25 a pair, of rearwardly extending arms 37.

In the form shown in Fig. 4, also, there is provided a similar arm 38. These arms may be, and preferably are, formed integral with the plate 33.

In the form shown in Figs. 1, 2 and 3, the arms 37 extend rearwardly through openings in the rear wall of the casing, and are provided exteriorly thereof with perforations 39, suitably formed to receive cotter pins 40; while in the form shown in Fig. 4, the arm is provided with a lug 41, perforated to receive a bolt 42 passing through the casing, and provided exteriorly of the latter with a nut 43. In this case, I prefer to secure the bolt to the rear in any appropriate manner, as by soldering the same thereto, for the reason that the head of the bolt is inaccessible, when the parts are being assembled and the nut screwed in place.

It will now be apparent that, in both forms just described, I have provided means inter-engaging with the arms to prevent the latter from being withdrawn toward the rear of the casing. By this means, the cover is securely held in place, yet may be quickly and conveniently removed to render the interior of the casing accessible for the purpose of inspecting or replacing the electric bulb.

Referring to Figs. 5 and 6, the form there shown differs from that already described, as regards the cover fastening means, in that in this case, the cover is hinged to the casing by appropriate hinges 44, and is provided opposite the hinges with a spring catch 45, herein in the form of a tongue having a rounded projection 46, entering a depression 47 in the casing, thereby holding the cover in its closed position. Herein,

the tongue is provided with an upturned portion 48, by means of which it may be lifted to disengage it from the depression for the purpose of opening the cover.

While I have herein shown and described certain forms or embodiments of my invention for illustrative purposes, and have disclosed and discussed in detail the construction and arrangement incidental to several specific applications thereof, it is to be understood that the invention is limited neither to the mere details or relative arrangement of parts, nor to its specific embodiments herein shown, but that extensive deviations from the illustrated forms or 75 embodiments of the invention may be made, without departing from the principles thereof.

Having thus described my invention, what I claim and desire by Letters Patent to procure is:

1. A lamp comprising, in combination, light-producing means; a casing therefor provided with an opening; a cover for said opening; light-transmitting means carried by said cover; and cover-fastening means extending from said cover toward an opposite wall of said casing, and having an operating portion which is accessible from the exterior of said casing.

2. A lamp comprising, in combination, light-producing means; a casing therefor provided with an opening; a cover for said opening; light-transmitting means carried by said cover; and cover-fastening means extending from said cover through an opposite exterior wall of said casing.

3. A lamp comprising, in combination, light-producing means; a casing therefor provided with an opening; a cover for said opening; light-transmitting means carried by said cover; and cover-fastening means including an element extending from said cover through an opposite exterior wall of said casing, and an element secured thereto beyond said wall.

4. A lamp comprising, in combination, light-producing means; a casing therefor provided with an opening; a cover for said opening; light-transmitting means carried by said cover; and cover-fastening means including a plurality of members extending from said cover through an opposite wall of said casing, and means interengaging therewith beyond said wall.

5. A lamp comprising, in combination, light-producing means; a casing therefor provided with an opening; a cover for said opening; light-transmitting means carried by said cover; and cover-fastening means including an element extending from said cover through an opposite wall of said casing, and an element extending therethrough beyond said wall.

6. A lamp comprising, in combination,

- light-producing means; a casing therefor provided with an opening; a cover for said opening; light-transmitting means carried by said cover; and cover-fastening means including a plurality of arms projecting from said cover through an opposite wall of said casing and provided beyond said wall with perforations, and fastening elements extending through said perforations to prevent said arms from being withdrawn toward the opposite side of said wall. 5
7. A lamp comprising, in combination, light-producing means; a casing therefor provided with an opening; a cover for said opening; light-transmitting means carried by said cover; cover fastening means extending from said cover interiorly of said casing and secured to the wall thereof. 10
8. A lamp comprising, in combination, light-producing means; a casing therefor provided with an opening; a cover for said opening; light-transmitting means carried by said cover; cover fastening means extending from said cover interiorly of said casing and secured to the opposite wall thereof. 15
9. A lamp comprising, in combination, light-producing means; a casing therefor provided with an opening; a cover for said opening; light-transmitting means carried by said cover, and cover fastening means comprising arms extending interiorly of said casing and engaging a wall thereof. 20
10. A lamp comprising, in combination, light-producing means; a casing therefor provided with an opening; a cover for said opening, said cover being provided with an aperture and an outwardly projecting flange forming an encircling seat; a light-transmitting element seated against said seat; and means for holding said element against said seat including an apertured element whose inner margin overlies the margin of said light-transmitting element, said apertured element providing means to secure the cover to the casing. 25
11. A lamp comprising, in combination, light-producing means; a casing therefor provided with an opening; a cover for said opening, said cover being provided with an aperture and an outwardly projecting flange forming an encircling seat smaller than said opening; a light-transmitting element seated against said seat and also smaller than said opening; and means for holding said element against said seat including an apertured element whose inner margin overlies the margin of said light-transmitting element. 30
12. A lamp comprising, in combination, light-producing means; a casing therefor provided with an opening; a cover for said opening, said cover being provided with an aperture and an outwardly projecting flange forming an encircling seat smaller than said opening; a light-transmitting element seated against said seat and also smaller than said opening; and means for holding said element against said seat including an apertured element whose inner margin overlies the margin of said light-transmitting element. 35
- opening; a light-transmitting element seated against said seat and also smaller than said opening; and means for holding said element against said seat including an apertured element whose inner margin overlies the margin of said light-transmitting element whose inner margin overlies the margin of said light-transmitting element; and a gasket interposed between said light-transmitting element and the overlying margin of the holding element. 40
13. A lamp comprising, in combination, light-producing means; a casing therefor provided with an opening; a cover for said opening, said cover being provided with an aperture and an encircling seat smaller than said opening; a light-transmitting element seated against said seat and also smaller than said opening; and means for holding said element against said seat including an apertured element whose inner margin overlies the margin of said light-transmitting element; and a gasket interposed between said light-transmitting element and the overlying margin of the holding element. 45
14. A lamp comprising, in combination, light-producing means; a casing therefor; a socket threaded through the wall of the casing to receive said light-producing means and coöperating means on the socket and casing to secure them against relative rotation when the socket is screwed home. 50
15. A lamp comprising, in combination, light-producing means; a casing therefor; a socket threaded through the wall of the casing to receive said light-producing means and coöperating means on the socket and casing to secure them against relative rotation and translation when the socket is screwed home. 55
16. A lamp comprising, in combination, light-producing means; a casing therefor; a socket extending through the wall of the casing to receive said light-producing means, said socket being flattened to present non-circular surfaces and coöperating surfaces carried by the casing to secure the two against relative rotation. 60
17. A lamp comprising, in combination, light-producing means; a casing therefor; a socket extending through the wall of the casing to receive said light-producing means, noncircular surfaces on the socket and coöperating surfaces carried by the casing to secure the two against relative rotation, and flanges carried by the casing to limit relative movement of translation. 65
18. A lamp comprising, in combination, light-producing means; a casing therefor; an opening in said casing; a light-transmitting element at said opening, and flanges adjacent said opening securing the light-transmitting element. 70
19. A lamp comprising, in combination, light-producing means; a casing therefor; an opening in said casing; a light-transmitting element at said opening, and members bridging said opening and securing the light-transmitting element thereover. 75

20. A lamp comprising, in combination, light-producing means, a casing therefor; an opening in said casing; a light-transmitting element at said opening, members bridging said opening, and flanges adjacent said opening which secure the light-transmitting element thereover.

In testimony whereof, I have signed my name to this specification in the presence of two subscribing witnesses.

ELLSWORTH A. HAWTHORNE.
